UNITED STATES PATENT OFFICE.

NOAH D. HAUVER, OF NEW YORK, N. Y.

TOY TRUMPET.

SPECIFICATION forming part of Letters Patent No. 249,347, dated November 8, 1881.

Application filed May 11, 1881. (No model.)

To all whom it may concern:

Be it known that I, NOAH D. HAUVER, of the city, county, and State of New York, have invented new and useful Improvements in Toy Trumpets or Whistles, of which the following is a specification.

This invention has for its object the production of a toy trumpet or whistle, chiefly for children's uses; and the invention consists in 10 making an elastic mouth-piece, as of india-rubber, in an oval or labial form at one end and of circular form at the other, and attaching it in any convenient manner to a tube of any desired length and form, and either of 15 wood, tin, paper, or any other suitable substance, as will hereinafter appear.

In the drawings, Figure 1 represents a trumpet complete and as made of metal. Figs. 2, 20 3, and 4 represent views of the mouth-piece, and as attached to a short wooden tube. Fig. 5 represents the mouth-piece as attached to a trumpet or tube of paper.

A represents the elastic mouth-piece, preferably made of india-rubber, and it may be 25 made of a piece of tubing, provided the end of the trumpet, as at B, upon which it is fastened, is properly flattened to give a flattened or oval shape to the tip end of the mouth-piece, as at C, Fig. 3, where the end of the tube is made 30 to represent two lips slightly opened, and which vibrate to and from each other when they are inserted in the mouth and a blast is blown through them, and so by their rapid vibrations produce sound-waves in the air. This mouth-piece may also be molded in the form shown, 35 and then attached to a trumpet or flaring tube either of metal, as shown at B, Fig. 1, or of wood, as shown at Figs. 2 and 5, by winding a cord around the lower end of the elastic tube, 40 as at D, or it may be fastened by a slight band or cord of rubber or in other convenient manner.

The form of tube at Figs. 2, 3, and 4 will

make a very sharp or shrill noise, and may be used as a pocket-whistle.

The trumpet at Fig. 5 is made of paper in the form used for cornucopias for holding candies, and in such a case the mouth-piece may be attached to a wooden form, as shown at Fig. 2, and then the small end of the paper tube 50 may be wrapped around it, as shown at E, Fig. 5, and then fastened by an elastic band, as at F, or in any other convenient manner, and in such a case the said paper tube may be used for holding candies, as in the ordinary manner 55 of such packages, and when they are used or emptied out the tube may be used as a toy trumpet.

A long trumpet made with such a mouth-piece may be used on board of vessels as a fog-horn, as the elastic lips are excellent substitutes for the reeds often used for such purposes.

The mouth-piece may be formed of two elastic pieces of rubber or leather and joined at 65 their edges by cement or a seam, and in this way serve to imitate the lips, as shown.

I therefore claim—

1. A mouth-piece for a trumpet or horn formed of two elastic lips, as hereinbefore set 70 forth.

2. The combination of a mouth-piece with two elastic lips, as described, and a trumpet or tube of any suitable form, as hereinbefore set forth.

3. The combination of a mouth-piece of elastic material with a paper tube that may serve as a wrapper for candies, &c., and adapted to be used as a trumpet, as hereinbefore set forth.

In witness whereof I have hereunto set my 80 hand and affixed my seal in the presence of two subscribing witnesses.

NOAH D. HAUVER. [L. S.]
